UNITED STATES PATENT OFFICE

1,991,068

CENTRAL STATION TRAFFIC CONTROL
SYSTEM

John P. Tarbox, Philadelphia, Pa., assignor to
The Gamewell Company, Newton Upper Falls,
Mass., a corporation of Massachusetts

Original application May 29, 1924, Serial No.
716,804, now Patent No. 1,769,555, dated July 1,
1930. Divided and this application May 8, 1929,
Serial No. 361,526. Renewed July 11, 1934

14 Claims. (Cl. 177—337)

My invention relates to crossing traffic control systems of the order of those employed for controlling street crossing traffic in cities, towns and villages, but more particularly of the order 5 of those used for controlling the heavy traffic of large cities.

This application is a division of my application S. N. 716,804, filed May 29, 1924, which is now United States Patent No. 1,769,555, granted July 10 1,930. Its outstanding object is the central station control and timing of signals. This control and timing will be better understood with some understanding at least of the aims and objects of 15 the system at large as disclosed in said application.

An outstanding defect in most, if not all, traffic control systems is the fact that traffic from one approach or from one direction is held up during the entire period during which traffic is permitted to move over the crossing from another approach or direction. Always such delays are 20 expensive, even in the moderate traffic of small towns and villages, but in the larger cities, especially in the largest, as in New York, the holding up of the large volumes of traffic is enormously expensive. The remedy of this defect is the central aim of my invention. Surrounding aims are the institution and preservation of an orderly movement of traffic over the crossing, the full 25 control of the rate of speed and volume of traffic, a secondary control over spacing and speeding of cars between crossings, the minimizing of traffic blocks at the crossing, the placement of each crossing upon an operating basis corresponding to its own peculiar conditions, the controlling of the relative proportions of main and cross traffic on principal highways, the establishment 30 of full co-ordination between traffic signals and traffic lines, the providing for the orderly and safe crossing of pedestrians, and the placement in the hands of the traffic officers of a positive control over every approaching and passing vehicle. There are yet many other aims of 35 a major and minor nature.

The central aim of the invention is accomplished by the projecting upon the pavement from an elevated point above the central area of the crossing of, a turntable of light and providing means under the control of the traffic officer to control the speed of rotation of the turntable so projected. This in and of itself solves the problems of expensive waiting and good order. According to the method of the invention, a car or cars in any approach to the crossing are required to enter empty pockets of the turntable 40

only and to remain in them while passing over the crossing area. The traffic is thus divided into ranks and files as it enters the crossing area and that order is preserved while it passes over the crossing area. The fixing of the number and sizes of the pockets outlined on the pavement 5 determines the depth and spacing of the ranks and files, and the control of the speed of rotation of the turntable outlined governs both the speed and the volume of the traffic.

The surrounding aims of the invention are accomplished through the variable projection transversely of the approaches of lines of light upon the pavement defining at one and the same time the limits of approach of vehicular traffic 10 and the paths of pedestrian traffic transversely of the crossing. Co-ordinated with the projection of these lines are open traffic signals so arranged that each approach and exit of the crossing is under the individual control of the traffic 15 officer. In furtherance of the method of the invention, the volume of traffic may also be varied by selectively varying the approaches from which the ranks and files are filled and by varying the character of certain of the pockets of the turntable and assignment of pockets of different 20 character to different kinds of traffic, the relative proportion of each class of traffic may be regulated. Stated from another viewpoint, the proportions of each kind of traffic are determined 25 by apportioning the area of the crossing surface between the different kinds of traffic and progressively rotating the area so apportioned or assigned. By these and other features of the 30 method and apparatus of my invention not only the central aim but each and all of the surrounding aims are attained. Moreover, there results a number of very important incidental advantages as will be more fully appreciated after the 35 invention is fully disclosed.

40 Referring to the drawings:

Figure 1 is a diagram of a time controlling apparatus.

Figure 2 is an axial cross section of the timing switch of the apparatus per se.

Figure 3 is a perspective of certain of its contacts.

Figure 4 is a diagram of the traffic signals controlled thereby.

Figure 5 is a crossing diagram of traffic under 50 control, and

Figure 6 is a perspective view of a local control box.

At the outset it should be noted that the color of lamps 22 and 23 respectively are the same in 55

all four directions. The designation system used, GE, GN, GW, GS, in which the letters E, N, W and S are prefixed by the capital letter G refer, for example, to a green lamp in which the east, north, 5 west and south directions are indicated by abbreviations for those directions. The same is true of the lamps WE, WW, WN and WS in which the prefix designates a white light. Reference may be had to the issued patent above referred to for 10 more detailed description.

Reverting now to Fig. 4 it will be noted that the switches of the groups EW and NS not only control the traffic signals, but also control the lamps 15 39 which serve to project the lines or bars of light 42 across the entrances or approaches to the turntable area from each of the highways. (See also Fig. 5.) In their forward positions illustrated, each of the switches controls a part of the associated traffic signal of the group to which it belongs. In its rearward position each of the switches 20 opens its traffic signal circuit and closes, or partially closes, the circuit of an associated one of the lamps 39. In technical parlance, the traffic signals and the approach control signals are by 25 these means "interlocked".

Specifically speaking, switches E of groups EW and NS control over circuit 55 that one of the lamps 39 designated AE (meaning the approach on the east), switches W control over circuit 56 30 a similar circuit of that one of the lamps 39 designated AW, and the switches N, S, E and W of group EW control the circuit 57 of the exit control lamps EE (meaning exit east) and EW (meaning exit west).

Similarly, the switches N and S of the groups 35 EW and NS control over circuits 58 and 59 respectively the circuits of approach control lamps AN and AS, while four switches of the group NS together control the series circuit 60 of exit control lamps EN and ES.

The circuits 55—56—58 and 59 emanate from common conductor 150 which in turn derives its potential from power main 154 by way of either of the emergency switches 29. Each such circuit 45 is interlocked as between switch groups EW and NS by being subjected to a control at back contacts 161 of corresponding switches in each of the two groups so that it is closed only when corresponding switches are thrown. Each of the circuits 57 and 60 emanates also from common conductor 150 and extends in series through normally open contacts 162 of the switches of its group 50 only. The circuits of all the lamps 39 of the group AN, EW, etc., are connected commonly to conductor 152 through which connection is made by branch 153 to main 159.

So organized, the invention may be applied to the control of extremely heavy traffic as illustrated in Fig. 5. The positions of the switches 60 indicated in Fig. 6 are those which will bring about the defining of traffic lines outlined in Fig. 5. The motor control arm 25 is set to regulate the rate of movement of the turntable and resulting- 65 ly the rate of speed of the vehicles on the crossing at, for example, ten and one-half (10½) miles per hour. During operation pursuant to the description thus far herein presented, the presentation of a green light 23 to the driver of a vehicle approaching the intersection along any of the highways, indicates to him that he is permitted to enter and move over the intersection 70 provided it is his purpose to leave the intersection by either the easterly exit EE or the westerly exit EW. Correspondingly, a white light 22 indicates to the driver of a vehicle approaching the

intersection along any of the highways that he is permitted to enter and move over the intersection provided it is his purpose to leave the intersection by either the northerly exit EN or the southerly exit ES.

In many instances it may be desirable, in order to facilitate traffic movement, to apportion certain sections of the turntable area solely for the use of traffic having certain characteristics. For example, as indicated by the dotted lines of Fig. 10

15, two pockets have been given that special character reserving them and that portion of the crossing area which they represent for east and west or crosstown traffic. It may be assumed that the dotted line bars of light are red or of 15 some special shape, while the full line bars of light are yellow, gold, or of some other special shape indicating their character pertaining to the accommodation of north and south traffic. These relations may be changed at will by operating 20 switch 47 or duplicates thereof controlling the special light sources 36. In the traffic condition shown in Fig. 5, it is assumed that the traffic officer in charge of the intersection has observed the slight congestion of traffic at the westerly exit EW, and 25 has moved the switch W of the group of switches EW to its forward position thus illuminating that part of the east and west traffic signal 23 designated GW. (Three parts are extinguished). Therefore, only traffic coming from the westerly 30 approach enters the special pockets 61 provided for east and west traffic. The extinguishment of the signal lamps GN, GE and GS prevents any intensifying of the congestion observed at the westerly exit EW and, assuming that the officer 35 controlling the signal lamps at the intersection has noted that such congestion extends into the turntable area and across the path of vehicles desiring to enter along the northerly approach AN, the officer has stopped the entry of traffic from 40 this approach by throwing off switch N of NS. Not only has this darkened the branch WN of the north and south traffic signal 22, but through the interlock circuit 58 it has illuminated the associated approach control lamp 39 pertaining to this 45 approach and laid down the line of light 42, which not only bars traffic from the turntable but establishes a pathway 62 for pedestrian traffic from the pavement 63 to the illuminated island 45. Observing this pathway, pedestrians know that 50 they are safe in crossing. The other three switches S, E and W, of the group NS are all forward, retaining closed the circuits of the corresponding parts of the north and south traffic signal 22 which they control. Thus traffic from 55 each of the other three approaches, west, south and east approaches, is apprised that the north and south line of traffic is opened to them. No other lines 42 are laid down at this time because the remaining approaches and exits are all open 60 for traffic. However, pedestrians noting an open pocket may cross from curb to island and the reverse by passing along with it. Indeed, if they observe that a vehicle in the pocket is not going to turn out at a given exit they may cross along- 65 side of the vehicle. A pedestrian may pass beside it providing the approaching vehicles do not obstruct his pathway. Three parts of the east and west traffic control signal 23 are dark. If now the fourth GW be made dark, not only would there be laid down a line 42 guarding the west- 70 ery approach AW, but corresponding lines would be laid down covering the easterly and westerly exits EW and EE.

The traffic officer can vary these signals and 75

associated lines of traffic at will to suit the varying traffic conditions. Should he desire east and west traffic alone, the four fingers of one hand can be used simultaneously to throw all of the 5 switches of group NS off. Or, he may use the associated operating knob 54 for this purpose. With all the switches of the NS group in their off position, lamps WN, WS, WE and WW are extinguished and bars corresponding to lines 42 10 would be laid down across the exits EN and ES. In a similar manner he can eliminate east and west traffic, and again re-establish north and south traffic by merely operating one knob 54 15 in one direction and the other in the opposite direction. Should he stop all traffic by throwing both knobs 54 into the off position, drawing them both toward him with one hand, he will not only stop all traffic but through series circuit 49 illuminate the generally visible emergency signal 20 24 and sound the emergency horn 24'. Had the traffic officer used four fingers to throw the switches N, S, E and W of both group EW and group NS to their off positions, and had there- 25 upon closed switch 50, lines of light 42 would be thrown completely around the crossing area, in addition to illuminating the visible emergency signal 24 and sounding the emergency horn 24'. In any event, pedestrians seeing the emergency signal and hearing the horn should not cross and 30 all traffic within the crossing area should clear out.

The general rules of traffic applying in the system so elaborated should be substantially as follows:

- 35 (a) Cars turning to the right must keep near the curb and may enter any open pocket.
 (b) Cars turning to the left must enter either pockets exclusively devoted to the direction of the left turn or the mouth of an otherwise open pocket pertaining to any direction of traffic. This simple rule minimizes occasion for blanketing of the inside cars on left turns.

Islands 45, midway between curbing, and lines 45 42 combine with the outer circle of the turntable to define zones for pedestrian traffic. Such islands may likewise be used in connection with simple installations such as are indicated in Fig. 1 of my aforesaid patent, and as indicated generally in Fig. 5 of the accompanying drawings. 50 To produce this result, it is but necessary to add the apparatus of Figs. 2 to 5, and the island lamps 43 and the zone lamps 39, similar to those used in Fig. 9 of my aforesaid patent, with appropriate circuits.

55 In Fig. 4 I show a continuation of the circuits of Fig. 1 in which the system of my invention is interlocked with the system of the halt and go type, so that a number of the crossing installations in times of extremely heavy traffic, such as 60 may not be taken care of by the turntable, may be connected together and operated as one by the halt and go method. This is simply accomplished by interpolating relays 64, 65 controllable from a central station, CG, which relays remove 65 the local control of the signals 22, 23 and 24 and render the signals subject to distant control over the circuits 66, 67, so that a number of successive signals in a given avenue of traffic may be controlled together from a central point at will. It is this subject matter which forms the basis of this divisional case.

70 Fig. 1 shows the apparatus which I have devised as a part of my invention for such a central control station, 68 is a chronometer of any standard circuit closing or circuit controlling make.

In this case it is illustrated as closing and opening from mains 154-159 at regular intervals periodically the circuit of the stepping relay 69 of the traffic signal timing device 70. This device comprises a fixed disc 71 graduated in minutes and fractions of minutes up to 8 (by way of illustration). Movable in planes parallel to this disc about concentric axes are four contact arms. One of these 72 is fixed to shaft 73 which carries ratchet 74 actuated by pawl 75 of the stepping relay 69. At 10 starting, arm 72 rests against a stop 76, and it is moved step by step, the steps corresponding to fractions of minutes from this stop, clockwise when relay 69 is operated by the chronometer 68. Arm 77 is frictionally or otherwise engaged with 15 arm 72 or its shaft 73 to be adjustable manually with respect to arm 72 but when released arranged to be carried step by step along with arm 72. Arms 78 and 79, however, are adjustable about fixed support 80 and frictionally associated with that support and each other so that while angularly adjustable they remain fixed with respect to dial 71 and are not stepped around with arm 72.

Electrically connected with the several arms of 25 the timing device 70 is a signal controlling switch 81 comprising a switch arm 82 moving commonly over two sets of interspersed contacts, the one 83 commonly connected to signal circuit 66 and the other 84 commonly connected to signal cir- 30 35 circuit 67. Arm 82 is rotatable step by step clockwise by stepping relay 85, pawl 86 and ratchet 87. In the timing device 70 the stepping arm 72 carries insulated from its body a contact 88 connected by conductor 89 in the circuit of stepping relay 85. Arm 77 carries a similar contact 90, connected by conductor 100 with a relay 101, the function of which relay is to effect flashing of the signals during energization thereof through a connection of arm 82 of the signal controlling 40 45 switch 81 by conductor 102 and its alternate contacts 103 to the main 154 through flashing commutator 105; and, during deenergization, to provide a current path to the main 154 excluding said commutator, through said contacts 103 and conductor 104. Arm 78 carries a contact 106 insulated from its body and connected by conductor 107 with the contacts of the series 83. Arm 79 carries a contact 108 similar to 106 but connected in this case by conductor 109 with the series 84 of the signal controlling switch.

50 Arm 72 and contacts 88 in addition to controlling stepping magnet 85 control the release magnet 110 of the timing device 70. This release magnet simultaneously withdraws both the stepping pawl 75 and the holding pawl 76. A weight 112 may then draw both arms 72 and 77 back to normal position against stop 76. In this position projection 113 on arm 72 engages and opens contacts 114 through which each of magnets 85, 60 65 101 and 110 lock up over a circuit generally denominated 115.

While Fig. 1 is diagrammatic in the showing of devices and circuits, in Fig. 2 I show by a transverse section how the arms 72, 77, 78 and 79 and their contacts may be associated together without interference and movement through substantially the 360° of the timing dial secured. All of the arms and contacts are mounted within a circular casing 116. Arm 72 is given the form 70 of a knob and with arm 77, which it carries frictionally, is supported from an elongated bearing 117 in the body of the casing proper at the back. Arms 78 and 79, however, are independently and frictionally supported in a bearing 118 formed 75

by a ferrule carried in the central opening of the dial 71 itself. The arms communicate by concentric thimbles respectively with insulating discs 119 of similar form which discs support concentrically metal rings 120 which in turn carry the respective contacts 88, 90, 106 and 108. These contacts may indeed be finger-like extensions from rings 120. The ends of the contacts are respectively shaped as indicated in Fig. 3 so that 5

10 90 and 88 may pass freely back and forth over the ends of 106 and 108. Connection is made with this group of contacts by brushes 121 which bear respectively on rings 120, which are insulated from each other, carried by a cross bar 76 in the 15 central vertical plane of the axis, and which are respectively connected with the circuits 89, 100, 107 and 109. The brushes are on the near side of bar 76 while the contacts of the group to which they pertain are on the far side. Thus 20 20 any or all of the contacts may be rotated clockwise away from bar 76 through substantially 360° until they come into engagement with the several brushes 121. So bar 76 constitutes a stop such as illustrated diagrammatically in Fig. 1, 25 defining the normal position of arms 72 and 77. Contacts 114 are carried by casing 116 and are opened by a pin stop 113 carried on that disc 119 associated with contact 88 and arm or knob 72.

Reverting again to Fig. 1, it will be seen that 30 30 the chronometer 68 also drives a recording device 123 which may carry in the usual course a sheet of recording material on its face laid off into 12 divisions corresponding to the hours of the day as is usual in time recorders.

35 Within the twelve circumferential divisions into hours of the day, the record carries a plurality of annular divisions into minutes according to the number of minutes represented on the dial 70 with which it is associated. Thus from zero 40 minutes at or near the center of the sheet there are serially arranged eight annular divisions in the illustration taken. Playing over the face of this record sheet are two recording pens 123', 124, the one connected by cord 125 with that disc 119 45 on which contact 108 is mounted and the other connected by cord 126 with that disc 119 upon which contact 106 is mounted. Pens 123', 124, being drawn toward zero position by suitable springs, it will be seen that with proper dimensions of connections, the pens will be drawn downwardly to those annular graduations indicative of the positions to which arms 78 and 79 are set. So set they will trace upon the record sheet 50 throughout the day the settings which arms 78, 79 are given at various times, making a complete 55 record of the signal operations.

Conductors 66, 67 leading from the interspersed groups of contacts 83, 84 associated with the respective arms 78, 79, are extended through double 60 pole switch A and double pole double throw switch B, both located at the control station of Fig. 1, unto the signal mains 66', 67' which extend to the local stations in parallel. The switch A serves merely to open the signal lines. The 65 switch B serves not only to open them but, when thrown into the upper closed position, to connect them both to one side of the source of power, we will say the positive side. When the signal lines are disconnected at switch A, however, they 70 may be independently and separately connected to the source of power by a single pole double-throw switch A' which is normally open and arranged to connect with the source of power back of the control station switch S.

75 In the local stations through which the control

line 66', 67' pass, as diagrammatically shown in Fig. 4, these signal lines connect directly through a local control double pole switch C with the local cut-in and cut-out relays 64, 65 previously mentioned. The opposite sides of these relays connect with the common conductor 163 and by way of conductors 152 and 153 to main 159. Relay 64 carries a bank of four contact pairs 127 normally opened as indicated but closed when the relay is energized to close the circuits of the several lamps of the signal 22 to the source of power in parallel to circuits 156 but independently of the local traffic officer's control switches EW and NS. Relay 65 carries a similarly arranged and operated group of contacts 128 to 15 connect the lamps of signal 23 to the source of power. Connection to the source of power in each case is made by way of common conductor 129 which extends through the normally closed contact 130 of relay 131 to conductor 132 which 20 can be traced to the source of power through a switch 133 associated with the switch 234, which is the main switch of the local station.

The circuit of relay 131 is jointly controlled by relays 64 and 65 through contacts 134 and 135 25 in such manner that relay 131 is energized when relays 64 and 65 are pulled up at the same time. In such case contact 130, through which the lamp circuits of signals 22 and 23 are connected to the source of power, is opened and normally opened 30 contact 136 is closed connecting signal 24 to the source of power.

Normally connected between the signal line 66', 67' and common conductor 152 are three pilot lamps, the one *ns* indicating the operation 35 of north and south traffic signals, another *ew* indicating the operation of east and west signals and a third *em* indicating the operation of emergency signals.

The system so organized may be used under 40 either local or central station control at will. During the quieter hours of traffic each day the operation will be under local control. During certain rush hours, however, the connected series of stations will be operated under central 45 control. Assuming operation to be proceeding under local control as heretofore outlined, and the rush hour to have arrived, the officer at the central station in order to undertake control of the series of stations at his command proceeds as follows: First, he sets arms 78, 79 and 77 in accordance with the number of minutes he desires to allot, north and south, east and west and warning signals, at the particular hour. In setting these arms, arm 72 is held by hand 50 against the top 76 so that it may not be drawn frictionally out of position when arm 77 is set. Next the motor which drives commutator 105 is started, though this motor may be connected directly across the mains and started when power 60 is put across the mains later. Thirdly, switches A and B opened during local control are closed to connect the signal lines 66', 67' to the signal control mechanisms. Fourthly, the switch S throwing on the power is closed.

Placing power on the mains places power by way of conductor 104, contact 103, conductor 102 on the arm 82 of the signal switch and through it on conductor 66 connecting with signal main 66'. This lights up pilot lamps *ns* in each of the 70 several local stations and immediately apprises the officers at the local stations that the time for central control has arrived and that the central office is operating its control. The local officer may or may not at the moment be ready to shift 75

from local to central control due to local traffic conditions which he alone is in a position to observe, such for example as a traffic jam in one direction or another or a certain congestion 5 which must be relieved. But having observed the pilot signal, it then becomes his duty to so regulate the conditions at his crossing as to, at the earliest possible moment, harmonize with the control from the central station which from this 10 time on is manifest upon the pilot lamps *ns* and *ew*. From this time on, as long as the central station continues its operation, these pilot lamps will indicate its functioning precisely, first the white lamp flashing, then the green lamp, etc. 15 Having relieved any special traffic condition which may have existed by special manipulation of his local switches, the officer having reference to the pilot signals then either operates his local switches in gang in substantial syn- 20 chronism with the central station signals on the pilot lamps until traffic is adjusted approximately thereto or else opens all his local station switches including switch 234, and at the same time closes switch 133. He then closes switch C which until 25 now has been open, thereby connecting relays 64 and 65 to the signal mains 66', 67', respectively. Then in addition to the pilot lamps, whenever power is placed upon either signal main, the corresponding signal 22 or 23, as the case may 30 be, is operated as a whole, each lamp in it being illuminated. Thus at the time the pilot lamp *ns* is illuminated, relay 64, which controls signal 22 governing north and south traffic, is energized. From this time on the local officer is expected to 35 retain all of his local switches in off positions and to retain closed switches 133 and C having to do with the central station control.

Reverting now to the central station at which control has been inaugurated, as soon as switch S 40 was closed, stepping magnet 69 started stepping arms 72 and 77 of the timing device toward arms 78 and 79. This stepping continues once each second or several seconds as may be desired, the arms being held in stepped position by retaining pawl 76, until arm 72 reaches arm 79, the 45 arm which indicates the time allotted for north and south traffic. In the meantime, however, contacts 90 and 88 have successively passed over contact 106 carried by arm 78 by which the time allotted to east and west traffic is controlled. 50 But this passage is of no effect, since contact 106 is at the time disconnected from the source of power, arm 82 of the signal switch being at the moment associated with the supplemental group 55 of contacts 84. The moment contact 90 of arm 77 reaches contact 108 of arm 79, power is applied through arm 82, contact 84, conductor 109, contacts 108 and 90 and conductor 100 to the commutator relay 101. The resultant energization 60 of relay 101 shifts the connection of signal switch arm 82 from direct connection with the source of power to indirect connection therewith through commutator 105. This shift may be made through make before break contacts if 65 necessary or other equivalent device to insure the full pulling up of relay 101. Relay 101 having pulled up locks up by conductor 115 through the now closed contacts 114 to the source of power. Therefore, for the interval of time 70 represented by the angle distended between arm 77 and the following arm 72, the north and south signals displayed at the various local stations, that is the signals 22, will be flashed in a characteristic manner instead of being displayed continuously. This is the indication to traffic that

a signal is about change, an indication corresponding to the present amber lamp signals which are in common use for the same purpose.

When contact 88 of arm 72 reaches contact 108 after this change interval, power is applied by conductor 89 from contact 108 to stepping magnet 85 of the signal switch 81. This steps arm 82 off the group of contacts 84 and unto the group 83. This takes power off of the main 66', de-energizes all of the relays 64, energizes instead the relay 65, shifting from the north and south signals 22 to the east and west signals 23. This shift takes place the moment arm 82 is shifted. Arm 82 and the spacing of contacts 83, 84 being properly proportioned, there need be no over-lapping of signals and no simultaneous energization of relays 64, 65 associated with the emergency signals. And the locking contacts of stepping relay 85 being adjusted with sufficient close-ness, operating independently of the stepping op-eration if need be, the stepping is full, complete and exact for then the energization of relay 85 is not interrupted by the stepping of arm 82 through which it receives its initial power and which it in turn controls. There are many devices known to 25 the art for adjusting such conditions and I contemplate using any of them which the situation may require. So, the traffic signals are set now for east and west traffic.

Relay 85 locks up over circuit 113' and through contacts 114 just as did commutator relay 101. When 30 88 and 108 contacted, however, in addition to closing the circuit of stepping magnet 85, they closed also the circuit through conductor 110' to the release magnet 110 associated with the stepping pawl 75 and the holding pawl 76. This magnet, too, locks up over circuits 114, 115 releasing both pawls. Instantly the weight 112 associated with the arms 72, 77 draws these arms back toward the stop 76. Contacts 88 and 90 in suc- 35 cession ratchet over contact 106 now connected to a source of power, but by reason of the inclina-tion of the ends of contacts 90, 88 (see Fig. 3) and the insulation of the undersides thereof, they do not effect electrical contact with contact 106 so 40 that no circuit is closed thereby and the east and west signals 23 continue to be displayed. Just before arm 72 reaches stop 76, pin 113 associated with contacts 114 engages the longer of these contacts and moves it away from the shorter, open-ing the locking circuits of all of the relays of 45 the control mechanism. This gives the mech-anism a fresh start, which it takes immediately, stepping magnet 69 and holding pawl 76 again cooperating. This time, when arm 77 reaches 50 arm 78 controlling the east and west signal, the device having been stepped through the arc repre-sentative of the time allotted to east and west traffic, contacts 90 and 106 place power on com-mutator relay 101 and the east and west signals 55 60 are flashed indicating the change in the same manner as were the north and south signals 22. Immediately following the interval of change, contact 88 contacts with 106, power is placed on stepping relay 85 which this time steps the con-trol arm 82 back to the group 84 which controls the north and south signals over line 66' and traffic is changed again to north and south traffic. 65

At the same moment release magnet 110 is again closed, the arms 72 and 77 are drawn back toward 70 normal, without this time having stepped so far as arm 79, the time allotted east and west traffic being less than that allotted north and south traffic. So only contact 90 ratchets past contact 106. This passage, however, is doubly of no effect 75

for not only does contact 90 ratchet pass on its reverse or insulated side, but also arm 106 has by this time been disconnected from the source of power through the stepping of arm 82.

- 5 Instead of operating the approach and exit line lights, AE, AW, etc., from the control switches direct, they may be operated through relays, and in this connection in case of a display of the emergency signal stopping all traffic, there may 10 be used a relay in parallel with the emergency signal, which relay extinguishes all of the approach and exit line lights, or at least the outer ones of them, whenever the emergency signal is operated, whereby pedestrians are not led to cross 15 the approaches by the normal appearance of the lines in disregard of the emergency signal.

As to modifications of the circuits themselves, there are many which may be made without departing in any way from the generic spirit of the 20 invention. There are, furthermore, many equivalents of detail which may be used. The apparatus as described has not yet been constructed, and it is anticipated that when it is constructed there will be found use for a few at least of the 25 scores of known equivalents and means for attaining the specified results in the realm of the electrical arts, particularly those arts pertaining to signalling and communication, such as the telephone and telegraph arts.

30 It is my belief that I have described the operations with sufficient clarity to enable anyone skilled in the arts to achieve the results claimed, with or without the aforementioned equivalents and means which he has at his command.

35 All these and other modifications which fall within the purview of the generic spirit are intended to be covered by the annexed claims.

What I claim as new and useful and desire to protect by Letters Patent is:—

- 40 1. A traffic signalling system comprising a plurality of local traffic control stations having routine traffic signals, a central control station, means operated from said central station for controlling said signals, means at each station for operating said signals manually at the local point, means at each local station for shifting control from the second named means to the central station control means, and pilot indicator means at each station connected to the central station 45 for indicating the instantaneous signalling operating condition established by the central station operating means.

50 2. In a traffic signalling system having two different indications, means for alternately displaying said indications for a period of time to indicate "stop" and "go", and means to intermittently display one of said indications at the end of its period to indicate "caution".

- 55 3. A shaft, a time controlled driving means adapted to rotate said shaft in one direction, means to engage and disengage said shaft to and from said driving means, but normally acting in engaging position, means to return said 60 shaft to a predetermined position when disengaged from said driving means, a stationary index mounted with its reference point at said predetermined position, a pair of stationary contacts, means for mounting said contacts about said 65 shaft in various fixed positions which can be determined from said index, a cooperating contact, means for mounting last said contact on said shaft for rotation therewith, in a position to come to said reference point when said shaft returns 70 to its predetermined position, and adapted to

engage the first said contacts when the shaft is rotated.

4. In a device as in claim 3, another contact, and means to adjustably mount said last named contact on said shaft for rotation therewith and in advance of the said co-operating contact.

5. In combination with the device of claim 3, a pair of conductors, means for selectively energizing said conductors, alternately operable upon engagement of said co-operating contact with 10 one of said stationary contacts to energize one of said conductors and upon engagement of said co-operating contact with the other of said stationary contacts to energize the other of said 15 conductors.

6. In combination with the device of claim 3, means to momentarily operate said disengaging means upon alternate engagement of the said 20 cooperating contact with said pair of stationary contacts.

7. In combination with the device of claim 3, a pair of conductors, means for selectively energizing said conductors, alternately operable upon engagement of said cooperating contact with one of said stationary contacts to energize 25 one of said conductors and upon engagement of said cooperating contact with the other of said stationary contacts to energize the other of said conductors, together with means to momentarily 30 operate said disengaging means upon alternate engagement of the said cooperating contact with said pair of stationary contacts.

8. In a traffic control system comprising a control station, traffic stations at a plurality of local points and each comprising—signals for governing traffic movements, means for effecting display of its associated signals pursuant to a progressive routine initiated responsive to said control station, means for local manual operation to control said displays, means for transferring control of said displays from said second named means to said first named means, and means at each local station effective during manual control for indicating the progression of the routine of displays established at other local stations responsive to initiation of said control station.

40 9. In a traffic control system comprising a control station, traffic stations at a plurality of local points and each comprising—signals for governing traffic movements, means for effecting display 45 of its associated signals pursuant to a progressive routine initiated responsive to said control station, means for local manual operation to control said displays, means for transferring control of said displays from said second named means to said first named means, and means at each local station independent of said traffic signals for continuously indicating the progression of the routine as initiated by said control station.

50 10. In a traffic control system comprising a control station, traffic stations at a plurality of local points and each comprising—signals for governing traffic movements, means for effecting display 55 of its associated signals pursuant to a progressive routine initiated responsive to said control station, means for local manual operation to control said displays, means for transferring control of said displays from said second named means to said first named means, and means at each local station for indicating the progression of the routine as initiated by said control station.

60 11. In a traffic signalling system having two different indications, means for effecting the display of a "go" indication for certain traffic during 70

a "stop" indication for other traffic, and means for alternately effecting "stop" indications for said first named and for said other traffic for predetermined intervals, and means to intermittently display one of said indications during a predetermined portion of one of said intervals.

5. 12. In a traffic signalling system having two different indications, means for alternately displaying said indications for periods of time for 10 respectively indicating "stop" and "go", and means to intermittently display one of said indications in a predetermined portion of one of said periods to indicate "caution".

13. In a traffic signalling system having two

different indications, means for alternately effecting display of said indications for periods of time respectively indicating "stop" and "go", and means to intermittently display one of said indications during the latter portion of one of said periods.

5. 14. In a traffic signalling system having two different indications, means for alternately effecting continuous displays of said indications for periods of time to indicate "stop" and "go", and means to intermittently display one of said indications during one of said periods.

JOHN P. TARBOX.
